UNITED STATES PATENT OFFICE.

ALBERT B. WRAY, OF SHREVEPORT, LOUISIANA.

JOURNAL-BEARING.

1,366,856.

Specification of Letters Patent. Patented Jan. 25, 1921.

Application filed August 3, 1920. Serial No. 401,000.

To all whom it may concern:

Be it known that I, ALBERT B. WRAY, a citizen of the United States, residing at Shreveport, in the parish of Caddo and State of Louisiana, have invented new and useful Improvements in Journal-Bearings, of which the following is a specification:

This invention relates to journal boxes and especially to journal boxes for the driving shafts of locomotives.

An object of the invention is to provide means for quickly and easily removing and replacing a lateral plate to or from the face of a locomotive driver between boxes without removing the driving wheels from the frame.

To this end the invention comprehends the novel form of interlocking engagement between the driver journal box and the lateral plate, so as to provide a ready and positive engagement, permitting the plate to be conveniently positioned and guarding against its accidental displacement.

The invention further consists of the following novel details of construction, combination and arrangement of parts, to be hereinafter more fully described and illustrated in the accompanying drawings:—

In the drawings:—

Figure 1 is a front elevation of a driving box with the lateral plate applied;

Fig. 2 is a fragmentary plan view of a portion of the driving box also showing the lateral plate in position;

Fig. 3 is a sectional view on the line 3—3 of Fig. 1;

Fig. 4 is a similar view on the line 4—4 of Fig. 1;

Fig. 5 is a fragmentary perspective view showing the face of the driving box;

Fig. 6 is a perspective view looking at the inner face of the lateral plate;

Fig. 7 is a similar view of one of the keys;

Referring to the drawings in detail, like characters of reference denote corresponding parts throughout the several views.

As illustrated in the drawings, there are various ways of carrying the invention into practice, one of which is shown in Figs. 1 to 7 inclusive. In these figures the numeral 14 represents the face plate of a driving box such as is employed with the driving shafts of locomotives. This box includes the usual crown brass 15 and cellar 16. It is custom-

ary in bearings of this character to position between the face plate 14 and the adjacent face of the driving wheel, a lateral plate and the present invention has to do with this plate and particularly to the means for securing the said plate to the driving box. For this purpose the face plate 14 of the driving box is vertically grooved as shown at 17 and the inner face of the lateral plate 18 is provided with lugs 19, the said lugs and grooves 17 being dove-tailed in cross section so as to provide an interlocking engagement between the plate and the driving box. These grooves and lugs extend a relatively short distance downward from the top of the driving box, preferably terminating short of the opening for the driving shaft. Also formed in the face of the plate 14 are transversely extending grooves 20, these grooves being positioned substantially diametrically with respect to the driving shaft.

The plate 18 is provided upon each side thereof with side wings or flanges 21, which are adapted to contact with the sides of the driving box. Openings 22 are formed in the plates 21, these openings registering with and being of substantially the same size and shape as the grooves 20. Transversely slidable keys 23, also of the same size and shape as the grooves 20, pass through the openings 22 and enter the said grooves to provide an interlocking engagement between the lateral plate and the driving box.

In order to prevent the accidental removal of the keys 23, outwardly extending lugs 24 are positioned at each end of the openings 22, these lugs being provided with aligned openings 25, which are adapted to register with an opening 26 provided in each of the keys 23. A bolt or pin 27 passes through the openings in the ears 24 of the key 23, to hold the latter in position. If desired a cotter pin 28 may extend through the bolt 27 beneath the nut 29 to prevent accidental removal of this nut. As an additional securing means, machine bolts 30 are passed through the side flanges 21 and engage openings in the sides of the face plate 14, a plate or malleable metal 31 having one end bent to engage one of the side edges of the head of the bolt 30 to provide a lock against the accidental removal of this bolt.

It is believed that when the foregoing description is read in connection with the ac-

companying drawings, that the construction, operation and advantages of the invention will be apparent. Various changes may be made in the form and proportion thereof and the right is reserved to make such changes as properly fall within the scope of the appended claims.

Having described the invention, what is claimed is:—

- 10 1. The combination with a driving box, of a lateral plate, side flanges carried by said plate for contact with each side of the driving box, vertically and transversely disposed grooves formed in the face of the driving box, dove-tailed lugs carried by the lateral plate for engagement with the vertically disposed grooves, transversely extending keys passing through openings in
- 15

the side flanges of the lateral plate and engageable with the horizontally disposed 20 grooves and means for preventing the accidental removal of the keys.

2. The combination with a driving box having vertically and transversely extending grooves in the face thereof, of a lateral 25 plate, side flanges carried by said plate for contact with each side of the driving boxes, means carried by the lateral plate for engagement with the vertically extending grooves, means extending inwardly from 30 the side flanges for engagement with the horizontally extending grooves and means for preventing accidental disengagement of the engaging means.

ALBERT B. WRAY.
